UNITED STATES PATENT OFFICE

2,494,361

LIQUID TREATING APPARATUS

Harry E. Scarbrough, Chicago, Ill., and Norman B. Jones, Ballston Lake, N. Y., assignors to General Electric Company, a corporation of New York

Application August 28, 1945, Serial No. 613,094

2 Claims. (CL. 134—133)

1

Our invention relates to liquid treating apparatus, more particularly to tank apparatus for quenching metallic articles, such as in the hardening of steel articles, and has for its object simple and inexpensive means for minimizing the splashing of the quench liquid when the articles are dropped into it.

In carrying out our invention we provide means located below the surface of the quench liquid for circulating the quench liquid so as to form a high velocity deflecting curtain under the surface of the liquid whereby turbulence is created in the liquid and splashing is minimized.

This splashing of the quenching liquid is especially disadvantageous when the heated articles are dropped from a heating furnace through an aperture in the lower wall of the furnace and a chute directly into the quench tank. In such installations the liquid has a tendency to splash upward for a very considerable distance and into the heating chamber where it vaporizes and produces carbon deposits which are very objectionable and may be the cause of failure of the heating apparatus.

For a more complete understanding of our invention reference should be had to the accompanying drawing, Fig. 1 of which is a fragmentary sectional view of the heat-treating apparatus embodying our invention, Fig. 2 is an enlarged fragmentary bottom view taken along the line 2—2 of Fig. 1, while Fig. 3 is an enlarged fragmentary sectional view taken along the line 3—3 of Fig. 1 looking in the direction of the arrows.

Referring to the drawing, we have shown our invention in one form in connection with a heating furnace having heat-refractory walls 1, forming a closed heating chamber in which is mounted suitable heating means, such as electric heating resistors (not shown). The articles to be heated are carried on a conveyor 2 extending lengthwise of the furnace and conveying the articles from the left toward the right, as indicated by the arrows. At the righthand end of the conveyor the articles drop through an opening 3 in the bottom wall of the furnace and in a predetermined vertical path through a vertical pipe or chute 4, into a liquid tank 5. As shown the bottom wall of the furnace is suitably connected around the opening 3 to the upper end of the chute. In the tank is a suitable quenching liquid, such as oil, maintained at a suitable level indicated by the dotted line 6. To form a seal against the ingress of air through the chute 4 into the furnace, the chute is extended a short distance below the surface of the liquid.

For the purpose of preventing splashing of the

quenching liquid in the tank upward through the chute into the furnace chamber when the articles are dropped into the quench tank, we provide a high velocity curtain of the quenching liquid or oil across the lower submerged end of the chute. This curtain of liquid is set up by means of a pump 7 driven by a suitable electric motor (not shown) for withdrawing a quantity of the liquid from the tank through an intake pipe 8 and forcing it back into the tank through a pipe 9. The pipe 9 is provided with two parallel closed end branches 10 and 11 mounted below the surface of the liquid on opposite sides of the lower end of the chute 4, these branches being provided each with a series of holes (Fig. 2) in its inner side, i. e., the side opposite the other branch, whereby the liquid from the pump is forced in jets 12 from these holes across the lower end of the chute 4. As shown in Fig. 2, the branches are provided respectively with holes 10a and 11a. Preferably, the jets of liquid are directed downward at an angle of substantially 30 degrees with the horizontal.

The opposed jets of liquid create a high velocity movement of the liquid in the tank horizontally and downwards across the lower end of the chute whereby a high velocity oil curtain is formed under the surface of the liquid across the lower end of the chute, together with turbulence of the liquid in the lower end of the chute, which minimizes splashing upwards in the chute. The liquid in the lower end of the chute is given a somewhat downward circulating movement as well as a horizontal movement with rippling of the surface of the liquid. This motion of the liquid minimizes splashing in itself and, in the event of any limited amount of splashing, the splashed liquid continues its horizontal movement and strikes the wall of the chute before reaching the furnace chamber. Preferably as shown, the chute is water cooled to prevent the vaporization of any splashed liquid, a water jacket 13 being shown around the chute.

The inlet pipe 8 is connected to withdraw liquid from a cooler intermediate zone of the tank. An inclined conveyor 14 is provided by means of which the cooled articles are lifted out of the quench tank.

For the purpose of prolonging the cooling period and to prevent nicking and deformation of the hot articles, we provide a plurality of resilient walls or plates for bouncing the articles in a zigzag path downward through the tank as described and claimed in a copending application, Serial No. 612,388, filed by Norman B. Jones and

August R. Ryan on August 24, 1945, assigned to the same assignee as this application.

As shown, three plates 15, 16, and 17 are provided arranged at right angles with each other. The plate 15 is mounted just below the chute in a substantially 45 degree angle with the vertical. A hot article dropped through the chute 4, as indicated by the arrows, strikes the plate 15 from which it bounces toward the right and downward onto the plate 16 and then back to the left onto the plate 17. From the lowermost plate 17 the article bounces toward the right into engagement with a pivoted hanging hinged plate 18 from which the article is deflected downward onto a second hinged plate 19 having a horizontal pivot 20. The free end of the plate 19 rides on the lower end of the inclined conveyor 14 so that the article rolls from the plate 19 onto the conveyor. Preferably the bounce plates and the hinged pivot plates 18 and 19 are provided each with a layer of resilient material, preferably made of a synthetic oil resisting rubber. As shown, the plate 15 is provided with a layer 21 of rubber on which the articles fall and similar rubber layers are provided on the plates 16, 17, 18 and 19. Each plate, for example, may be made of $\frac{1}{4}$ " steel material covered with a $1\frac{1}{2}$ " thick layer of rubber. Preferably, the rubber layer is suitably vulcanized to the steel, although the two may be secured together by bolts or rivets.

Preferably, the pump 7 is provided with a second outlet pipe 22 which extends into the lower end of the tank below the plate 17 for the purpose of creating an upward circulation of the heated oil. This pipe 22 terminates in a horizontal closed end portion secured to the lower side of the bounce plate 17 and provided with a series of apertures 23 registering with similar apertures 23a in the bounce plate. The liquid is forced by the pump through these apertures.

A second delivery chute 25 is provided extending vertically downward into the upper end of the tank through which additional articles may be dropped or lowered into the tank if desired.

While we have shown a particular embodiment of our invention, it will be understood, of course, that we do not wish to be limited thereto since many modifications may be made and we therefore contemplate by the appended claims to cover

any such modifications as fall within the true spirit and scope of our invention.

What we claim as new and desire to secure by Letters Patent of the United States is:

- Liquid treating apparatus comprising a tank for containing a quantity of liquid, a chute extending downward into said tank through which articles are dropped into said tank, a conduit in said tank adjacent the lower end of said chute and below the surface of the liquid in said tank, and pump means connected to said conduit for supplying liquid to said conduit under a predetermined pressure, said conduit being provided with aperture means for directing a curtain of liquid across the lower end of said chute thereby to prevent splashing of the liquid upward into said chute by articles falling into said tank.
- Liquid treating apparatus comprising a tank for containing a quantity of liquid, a chute extending downward into the upper end of said tank below the surface of said liquid through which articles are dropped into said tank, two conduits in said tank spaced apart on opposite sides of the lower end of said chute, and pump means adjacent said tank for withdrawing liquid from said tank and supplying liquid to said conduits, said conduits being provided with apertures in their adjacent walls for directing opposed jets of liquid in a downward direction across the lower end of said chute thereby to prevent splashing of the liquid upward into said chute by articles falling into said tank.
